C. A. LY.FORD

SUBLIMATION APPARATUS

Filed April 2, 1920

By his Attorneys
Pennie Davis Marvin & Edmunds

UNITED STATES PATENT OFFICE.

CHAUNCEY A. LYFORD, OF EAST AURORA, NEW YORK, ASSIGNOR TO NATIONAL ANILINE & CHEMICAL CO., INC., OF NEW YORK, N. Y., A CORPORATION OF NEW YORK.

SUBLIMATION APPARATUS.

Application filed April 2, 1920. Serial No. 370,802.

- This invention relates to an improved sublimation apparatus for the sublimation of chemical materials by the use of superheated steam or other heated gas or vapor.
- 5 In the ordinary forms of sublimers designed for work at high temperatures, difficulty is encountered with many materials because of local overheating of the material where it comes in contact with the walls 10 of the container. Such overheating may result in charring or gumming of the material near the heated walls, while the material away from the walls is heated to a much lower temperature. Owing to such differences 15 in temperature it is sometimes difficult to determine at just what temperature the process is being operated, and whether parts of the material are sufficiently heated or other parts overheated. The provision of 20 agitators, for agitating the material during sublimation reduces this difficulty, but the difficulty may nevertheless be encountered to a greater or less extent even when an agitator is provided. Moreover, where the 25 material being sublimed is of a pulverulent or pulverizable character, the agitator may pulverize it so finely that, where a transporting medium is employed, the fine dust of the crude material is carried over with the 30 transporting medium and with the vapors of the material being sublimed, so that the sublimate is contaminated by impurities.
- The present invention relates to an improved apparatus intended more particularly 35 for the sublimation of material which does not fuse together during sublimation but which is of a porous and permeable character. The invention is well adapted for the sublimation of materials which have not been finely ground, but which exist in the 40 form of lumps, for example, such as come from the drying of material taken from a filter press, where the material is of a porous character and where the larger lumps have 45 been broken up.
- According to the present invention, the material to be sublimed is placed in a suitable container or receptacle which is suitably heated and which has a perforated bottom 50 upon which the material is supported; and the superheated steam or other gas or vapor is introduced beneath the perforated bottom and caused to pass up therethrough, into and through the material supported
- thereon. The superheated steam or other gas or vapor passes vertically up through the charge of material and subjects it to a uniform temperature appropriate to the sublimation operation. The material sublimed, together with the transporting medium, are 60 removed from the sublimation receptacle and carried to a suitable condenser where the sublimate is separated in a solid state.
- The invention includes various features of improvement.
- 65 In the accompanying drawings I have illustrated, in a somewhat diagrammatic and conventional manner, two forms of apparatus embodying the invention and the invention will be further described in connection therewith.
- In the accompanying drawings:
- 70 Fig. 1 shows the sublimation apparatus in elevation and with parts in vertical section; and
- 75 Fig. 2 is a vertical sectional view of a modified form of apparatus.
- In the apparatus of Fig. 1 the receptacle or container 1 is provided with a suitable cover 2 having a charging manhole 3 therein and having an outlet conduit 4 for the sublimate, this conduit leading to the condenser 14. The receptacle or container 1 has a perforated bottom spaced away from the bottom of the container itself and suitably supported (by means not shown).
- 80 This perforated bottom is made up of a perforated sheet metal plate 6 having a screen 7 supported thereby and upon which the charge of material to be sublimed is supported. The screen 7 prevents smaller particles from falling through into the chamber 9 and insures a more uniform distribution of the heating and transporting medium passing upwardly therethrough. The perforated or false bottom divides the vessel or receptacle 1 into a larger upper chamber 8 and a smaller lower chamber 9. The chamber 8 has a side opening 10 for the purpose 85 of removing the exhausted material at the end of the operation.
- 90 The container 1 is surrounded by a heating jacket 11 intended for oil or other suitable medium. The oil jacket is heated and maintained at the desired temperature in any suitable manner, as by direct firing in the furnace 13. Thermometer wells 5 and 12 are suitably arranged in the chamber 8 and

in the oil jacket. It will be evident that the oil used in the heating jacket should have a high flash point where the apparatus itself requires a high temperature for its operation. The temperature of the oil or other heating medium in the jacket will vary with the material to be sublimed, but it should be maintained only at about that point which will compensate for the possible heat losses of the superheated steam or other transporting medium passing through the apparatus. All the exposed metal parts of the apparatus should be covered with magnesia packing or other insulating covering (not shown) to prevent condensation of the sublimate.

Where superheated steam is supplied as the transporting medium it is superheated to the proper temperature in the superheater 23 which may be of any suitable construction, and which is shown as an oil-fired superheater having oil and air supply pipes 24 and 25. The superheated steam, superheated to the proper temperature, is conveyed from the superheater through the pipe 26 and discharges at 27 into the lower chamber 9 below the false bottom. From this chamber it passes up through the perforated bottom in a uniform manner and then passes up through the charge of material to be sublimed, serving to heat the material in a uniform manner and to the proper temperature. The sublimate is carried over with the superheated steam, through the pipe 4, to the condenser. The pipe 29 from the superheater to the top of the chamber 8 permits an excess of superheated steam to be introduced to assist in sweeping the vapors from the chamber to the condenser. The condenser illustrated is provided with a water jacket 15 and with scrapers 16 for keeping the inside cooling surfaces free from any sublimate that condenses thereon, thereby promoting the cooling effect of the water jacket. The condenser is also provided with spray nozzles 18 and 19, one for spraying water downwardly at the top and the other for spraying water upwardly from the bottom. Water is supplied through the pipe 17. The sublimate and the water condensed in the condenser are passed to a filter for the separation of the sublimate from the water. As illustrated, this filter is in the form of a perforated plate 20 having a canvas layer 21 thereon. The sublimate is collected on the filter while the water is drawn off through the pipe 22 to a suction pump (not shown). In the operation of the apparatus, the charge to be sublimed, preferably in the form of small lumps, is charged into the compartment 8 through the manhole 3, the manhole cover is secured in place, the oil jacket is heated to a suitable temperature, and the superheated steam is introduced

through the pipe 27 from the superheater into the lower chamber 9 from which it passes upwardly through the false bottom and through the charge supported thereby. The chamber 9 has a bleeder or draw-off pipe 28 for drawing off any water or condensation such as forms during the early part of the operation. When the steam no longer condenses, the discharge opening 28 is closed. The temperature of the sublimation and of the oil jacket are readily determined by thermometers placed in the thermometer wells 5 and 12. The temperature is raised to a suitable temperature for the sublimation and is maintained until the sublimation is completed. Steam at a lower temperature is then preferably passed through the apparatus to cool it and the residue is then discharged through the opening 10.

The sublimate together with the superheated steam pass through the pipe 4 to the condenser where condensation is effected either by means of the water jacket 15 or by means of the spray introduced through the spray nozzles 18 and 19, or partly by the water jacket and partly by the spray, and the sublimate is collected on the filter 21 and separated from the condensed steam.

In the apparatus of Fig. 2 the corresponding parts are indicated by the same reference numerals with the suffix "a" appended thereto. In the construction illustrated in this figure, however, the oil jacket is omitted and a steam jacket is provided adapted to be heated by the same steam which is used in carrying out the sublimation operation. The apparatus comprises the receptacle 1^a having a perforated bottom for containing the charge of material to be sublimed, and this receptacle is surrounded by an outer receptacle 11^a which provides an annular steam jacket and a bottom compartment 9^a for the superheated steam introduced through the pipe 26^a. The apparatus is provided with suitable insulating means such as a magnesia covering (not shown).

In the operation of this apparatus, the cover is removed, the receptacle 1^a, which can be removed from the outer vessel 11^a, is charged with the material to be sublimed, the cover is replaced, and the operation is then carried on in a manner similar to that above described, by the introduction of the superheated steam through the pipe 26^a. This superheated steam has the double function of supplying the heat for the heating jacket and the steam for the sublimation, so that the receptacle 1^a is surrounded by steam at substantially the same temperature as that which is passing through it for effecting the sublimation. Proper regulation of the steam temperature thus enables the entire sublimation operation to be properly regulated in temperature. The apparatus illustrated in Fig. 2 is adapted for smaller

scale operations than that of Fig. 1, although the same principles of construction and the same combined use of the steam as the heating means and as the transporting means is equally applicable to larger sized apparatus.

The rate at which the sublimation takes place will depend in part upon the rate at which the superheated steam is supplied, as well as upon the temperature of the steam, 10 the porosity of the charge, etc. At the outset of the operation the charge will be progressively raised in temperature by the superheated steam, and, particularly if the material undergoing sublimation is rapidly 15 sublimed, the temperature within the receptacle may be materially lower than that of the superheated steam introduced. It will usually be some time after the process begins before the charge is gradually heated 20 to its maximum temperature, and it is usually desirable to secure this gradual and progressive increase in temperature so that the subliming operation will be continuous and progressive. Near the end of the sublimation the temperature can with advantage be somewhat increased to complete the 25 sublimation of materials which have not been previously sublimed.

The physical character of the sublimate 30 will vary greatly with the method of condensation. The use of a finely divided water spray in the condenser tends to produce a finely divided sublimate, and the condensed steam and added water spray serve to dissolve soluble constituents and thereby purify 35 the sublimate. It is therefore of advantage to effect the condensation of the sublimate by means of a water spray so that the sublimate will be obtained in a purified state 40 and in a finely divided condition well adapted for subsequent treatment.

From the above description it will be seen 45 that mechanical agitation of the charge undergoing sublimation is avoided, and that local overheating or uneven heating of the charge is avoided or reduced to a minimum, while the entire charge is subjected to the uniform heating action of the superheated steam which serves as both the heating and 50 the transporting medium. As a result, the production of fine dust, such as may result from mechanical agitation, is avoided, and the carrying over of fine dust with the steam is correspondingly reduced. The only agitation to which the charge is subjected is 55 that incident to the passage of the steam upwardly therethrough, but this will ordinarily be so slight that it will be entirely unobjectionable, and may even be desirable in

promoting the uniformity of distribution of the steam through the material.

The apparatus of the present invention is applicable to the sublimation of organic or inorganic material from a non-sublimable material, and particularly where the material does not fuse together, but maintains a solid state throughout the operation. Materials can thus be sublimed which would be easily disintegrated into an impalpable powder if subjected to agitation, without any appreciable production of such a powder or carrying over of fine material with the transporting medium. The invention is also applicable to the sublimation of material for the purpose of changing its physical state 70 and where purification from a non-sublimable residue is not effected. The invention is of particular value, however, for the separation of sublimable material from a residue of a bulky or light-weight character. 80

The improved apparatus of the present invention is of special value for the sublimation of benzanthrone and the production of a purified benzanthrone from crude benzanthrone; but I do not claim herein the 85 method of sublimation of benzanthrone, etc., inasmuch as this forms the subject-matter of a separate process, application Serial No. 370,801, filed of even date herewith.

I claim:

1. A sublimation apparatus comprising a container for the material to be sublimed, means for introducing steam into the container beneath said material, means for introducing steam into said container above 95 said material and means for condensing the sublimed material.

2. A sublimation apparatus adapted for the sublimation of organic chemical materials without local overheating of the material, comprising a perforated support for supporting the material to be sublimed, means for supplying and introducing superheated steam beneath said supporting means, means for supplying and introducing superheated steam above said supporting means, and means for condensing the sublimed material. 100 105

3. A sublimation apparatus comprising a container for the material to be sublimed, means for passing superheated steam through said material, means for simultaneously passing steam over the surface of said material, and means for condensing the sublimed material. 110 115

In testimony whereof I affix my signature.
